(57) **CLAIM**

The ornamental design for a softbox chuck, as shown and described.

DESCRIPTION

FIG. 1 is a perspective view of my new design, showing a softbox chuck;

FIG. 2 is another perspective view thereof;

FIG. 3 is another perspective view showing the softbox chuck in an alternate position;

FIG. 4 is another perspective view showing the softbox chuck in another alternate position;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

In the drawings, the broken lines show portions of the softbox chuck that form no part of the claim.

1 Claim, 10 Drawing Sheets
